Patented Mar. 10, 1914.

Fig. 1

UNITED STATES PATENT OFFICE.

BENJAMIN WEXLER, OF BROOKLYN, NEW YORK, ASSIGNOR TO THE PEELLE COMPANY, OF NEW YORK, N. Y., A CORPORATION OF NEW YORK.

LATCH FOR ELEVATOR-DOORS.

1,089,451.

Specification of Letters Patent.

Patented Mar. 10, 1914.

Application filed August 7, 1912. Serial No. 713,724.

To all whom it may concern:

Be it known that I, BENJAMIN WEXLER, a citizen of the United States, and resident of Brooklyn, in the county of Kings and State of New York, have invented certain new and useful Improvements in Latches for Elevator-Doors, of which the following is a specification.

The invention relates to improvements in latches for elevator-doors, and has particular reference to self-closing fireproof doors leading from the several floors of a building to an elevator-shaft; and the object of the invention is to provide for each door a spring latch arranged for actuation only when the car is at rest at that floor of the building to hold the door in open position, and means to release said latch and allow the door to close when the car leaves the floor in either direction. In latches as ordinarily constructed, the car, as it passes the several floors, successively engages the several door-latches, causing an unnecessary wear upon the parts and an objectionable noise from the movement thereof, particularly noticeable in buildings of considerable height in which the floors are numerous and the speed of the car relatively high. And further objects of the invention include the arrangement with the latch of a recoil spring to facilitate the normal closing movement of the door, and of a fusible-link connection adapted to operate with the latch in the event of fire to close the door independently of the car.

In describing the invention in detail, reference is had to the accompanying drawings, forming a part of this specification, and wherein like characters of reference are used to designate like parts throughout the several views, and in which:

Figure 1 is a side elevation of an elevator-doorway, having a two-part vertically slidable door provided with the improved latch embodied in the present invention; Fig. 2, a transverse section of the doorway, shown in relation to the door sections and latch; Fig. 3, an enlarged ground plan, with the adjacent parts shown partially in section; Fig. 4 an enlarged side view of the latch, with the several parts positioned for holding the door in open position, and shown in relation with the recoil spring and fusible-link connection; and Fig. 5 shows the parts of the latch as positioned at the be-

ginning of the closing movement of the door, the recoil spring and fusible-link connection being omitted.

Numerals 1 and 2 designate respectively the adjacent portions of the upper and lower sections of a two-part fire-proof elevator-door, to the lower section of which is secured a carrier-bar 3, connected at its opposite ends to the flexible cables or chains 4, which lead over the carrier-wheels 5, and are secured to the upper door section. The wheels are mounted upon guide-rails 6, which are fixed to the wall of the elevator-shaft and provided with interior angles 7 for slidingly receiving the usual guide-blocks 8, secured to the door-sections, which latter, as thus mounted, are adapted for vertical movement from and toward each other for opening and closing a doorway 9, leading to the elevator-shaft, the upper door-section being more heavily constructed to have an over-balancing effect upon the lower section to cause a self-closing action of the door when opened.

Within the elevator-shaft is movably supported a car of ordinary construction, indicated by the fragmental portions of an upright 10 and a platform 11, to the latter of which is secured a hanger 12, carrying a cam 13.

Upon one of the guide-rails 6 is fixed a latch-frame 14, having a fixed hinge-pin 15, for pivotally supporting, intermediate its ends, a latch-lever 16, on the upper end of which is fixed a pin 17 for hingedly supporting a latch-head 18. The lower edge of this head is beveled and engages a correspondingly beveled shoulder 19 formed on the latch-lever which serves as a stop to limit the relative movement of the head in one direction about the pin 17, the head being normally retained against the stop by the action of the spring 20, the upper end of which engages the rearward edge of the head, while its opposite or lower end is coiled about and fixed to the pin 21, secured to the latch-lever. The latch-head, as thus yieldingly supported upon the lever, jointly swings therewith about the pin 17, and is normally held in a projected position for engagement with the door, as shown in Fig. 4, by the action of the spring 22, the upper end of which engages the lower edge of the latch-lever, while its opposite end is coiled about and fixed to the pin 23, secured to the latch-

frame 14. The lower end of the latch-lever is also provided with a slot or perforation, through which extends the shank 24 of the shoe 25, the latter being adjustably fixed in 5 suitable position by the set-screw 26, provided in the lever. The shoe is adapted to engage the cam 13 fixed upon the car when the latter is at rest, but is normally held in disengagement therefrom by the spring 22, 10 to permit the free movement of the car while the doors are closed. Also secured to the latch-frame 14, are a pair of guide-blocks 27, having perforations in which is slidably mounted the recoiler-stem 28, provided 15 at its upper end with a contact head 29, and at a point intermediate the guide-blocks with an adjustable thrust collar 30, which engages the upper end of a compression spring 31, arranged to encircle the stem 28 20 and bear upon the lower guide-block.

The actuation of the recoiler is effected by the manual operation of opening the door, wherein the bottom edge of the carrier-bar 3 of the lower door section in its lowermost 25 position engages the contact-head 29 to lower the same and compress the recoil spring 31, which is retained thus compressed by the engagement of the latch-head 18 with the upper edge of the carrier-bar 3, the downward 30 movement of this bar being positively limited by its engagement with the ledge 32, formed on the latch-frame 14. Upon the release of the latch-head 18, the spring 31 serves to upwardly urge the carrier-bar and 35 its connected lower door section, giving the same an impulse to facilitate the closing of the door by overcoming its inertia of rest.

As shown in Figs. 2 and 4, the latch-head 18 is in its outward or projected position, the 40 elevator-car being at rest at that floor of the building, and the door therefor in open position. In the operation of opening the door, the lower section thereof is manually depressed, the carrier-bar 3 thereon engaging 45 the latch-head 18 and causing the same to swing inward about its pivotal support 17 against the action of the yielding spring 20, which latter upon the continued movement of the door downwardly urges the head into 50 engagement with the upper edge of the carrier-bar to hold the door in open position while the car is at rest, the cam 13 on the latter engaging the shoe 25 to prevent movement of the latch-lever during the opening 55 movement of the door and while the latter is held in open position. When the car leaves the floor in either direction, the cam thereon is disengaged from the shoe, and the upward action of the self-closing door in connection 60 with the recoil-spring 31 is sufficient to cause an inward movement of the upper end of the latch-lever 16 about its pivotal support 15 in opposition to the yielding action of the spring 22, as indicated in Fig. 5; the engaging 65 surface of the connected latch-head 18

being suitably shaped with respect to the line of action of the contacting carrier-bar 3 to effect this inward movement. Upon the disengagement of the carrier-bar from the latch-head, the latch-lever is free to swing 70 backward into normal position with its shoe 25 out of the car line of movement.

In the event of the door being manually opened when the car is not in position, it will be obvious that the latch as thus constructed will not hold the same in open position, but will allow the door to automatically close and guard against accident. Also to provide in the event of an adjacent fire for the automatic closing of the door when 80 latched in open position while the car is at rest, a bar 33, having a cam-shaped portion 34, is slidably mounted in the guide-blocks 27, fixed upon the latch-frame 14. At its lower end the bar 33 is connected to one end 85 of a tension spring 35, the opposite end of the latter being fixed to the latch-frame and held in tension thereby to exert a pulling stress upon the bar in opposition to the wire 36, connected to the upper end thereof. 90 From its connection at the upper end of the bar the wire is led upwardly to an adjacent point within the building where its opposite end is connected to an ordinary fusible-link 95 37, which normally acts in opposition to the spring 35 to hold the bar in its upper or clear position with respect to the latch-head 18. In the event of an adjacent destructive fire the fusible link 37 is parted and the resistance of the wire 36 is overcome, permitting the tension of the spring 35 to effect a downward movement of the bar, which movement serves to engage the cam portion 34 thereof with the pin 38, fixed to the latch-head 18, causing the latter to be retracted 100 for the release of the carrier-bar, and permitting the door to automatically close independently of the car.

The several parts comprising the latch being thus operatively associated upon the 110 latch-frame 14, it will be obvious that the same may readily be adjusted and secured to the guide-rail or other point adjacent the elevator-car, and, in situations requiring the use of relatively wide doors, latches operating upon both ends of the carrier-bar may be employed.

With the use of the above-described latch it will be clear that upon the opening of the elevator-door the same will remain open only 12 when the car is suitably aligned therewith under normal conditions of temperature.

What I claim as my invention and desire to secure by Letters Patent, is:

1. The combination with a self-closing 13 elevator-door, of an elevator-car, a latch-lever yieldingly supported adjacent said door and normally held from engagement with said car, a latch-head yieldingly supported on and normally projecting from 1

said latch-lever, means on the door adapted to engage the latch-head and actuate the latch-lever, and means on the car for arresting the movement of the latch-lever 5 when the car is at that floor of the building to hold the door in open position and for releasing said lever when the car leaves the floor in either direction.

2. The combination with a self-closing elevator-door having a carrier-bar secured thereto, of an elevator-car, a latch-lever 10 yieldingly supported adjacent said door and normally held from engagement with said car, a latch-head yieldingly supported on and normally projecting from said latch-lever and adapted to be engaged by the carrier-bar, a spring-recoiler adjacent said latch-head and adapted to be engaged by said carrier-bar, and a cam fixed on said car 15 and adapted to arrest the movement of the latch-lever when the car is at rest at that floor of the building.

3. The combination with a self-closing elevator-door, of an elevator-car, a latch-lever 20 yieldingly supported adjacent said door and normally held from engagement with said car, a latch-head yieldingly supported on and normally projecting from said latch-lever, means on the door adapted 25 to engage the latch-head and actuate the latch-lever, means on the car for arresting the movement of the latch lever when the car is at rest at that floor of the building, and latch-releasing means including a fusible-link connection adapted to actuate said latch-head independently of the latch-lever. 30

4. The combination with a self-closing elevator-door having a carrier-bar secured thereto, of an elevator-car, a latch-lever 35 yieldingly supported adjacent said door and normally held from engagement with said car, a latch-head yieldingly supported on and normally projecting from said latch-lever and adapted to be engaged by the carrier-bar, a spring-recoiler adjacent said latch-head and adapted to be engaged by said carrier-bar, a cam fixed on said car and adapted to arrest the movement of the latch-lever when the car is at rest at that 40 floor of the building, and latch-releasing means including a fusible-link connection

adapted to actuate said latch-head independently of the latch-lever.

5. The combination with a self-closing elevator-door, of an elevator-car, a latch-frame 55 supported adjacent said door, a latch-lever yieldingly supported on said frame, a latch-head yieldingly supported on said latch-lever and movable therewith, a spring-recoiler supported on said frame, means on the door adapted to engage said latch-head and spring-recoiler, and means on the car adapted to arrest the movement of the latch-lever.

6. The combination with a self-closing door, of an elevator-car, a latch-frame 65 supported adjacent said door, a latch-lever yieldingly supported on said frame, a latch-head yieldingly supported on said latch-lever and movable therewith, means on the door adapted to engage said latch-head, means on the car adapted to arrest the movement of the latch-lever, latch-releasing means 70 yieldingly mounted upon said latch-frame and adapted to retract said latch-head, and a fusible-link connection normally holding said latch-releasing means from engagement with the latch-head.

7. The combination with a self-closing door, of an elevator-car, a latch-frame supported 80 adjacent said door, a latch-lever yieldingly supported on said frame, a latch-head yieldingly supported upon said latch-lever and movable therewith, a spring-recoiler supported upon said frame, means on the door adapted to engage said latch-head, and spring-recoiler, means on the car adapted 85 to arrest the movement of the latch-lever, latch-releasing means yielding mounted upon said latch-frame and adapted to retract said latch-head, and a fusible-link connection normally holding said latch-releasing means from engagement with the latch-head.

Signed at New York in the county of New 95 York and State of New York this 25th day of July, A. D. 1912.
